UNITED STATES PATENT OFFICE

100,885

DESIGN FOR A SHOE OR SIMILAR ARTICLE

Adolph Wertheim, New York, N. Y.

Application May 4, 1936, Serial No. 62,453

Term of patent 3½ years

To all whom it may concern:

Be it known that I, Adolph Wertheim, a citizen of the United States, residing in New York city, in New York county, in the State of New York, have invented a new, original, and ornamental Design for a Shoe or Similar Article, of which the following is a specification, reference being had to the accompanying drawing forming part thereof.

Figure 1 is a plan view of a shoe showing my new design.

Figure 2 is a side elevation of the shoe, partly in perspective.

The dominant feature of the present design resides in the part shown in full lines in the drawing and comprising a bow having an arcuate portion extending above the instep of the shoe, the arcuate portion having ends crossing each other at the instep of the shoe, said ends being attached to the vamp near the instep of the shoe.

I claim:

The ornamental design for a shoe or similar article, substantially as shown and described.

ADOLPH WERTHEIM.
